J. L. McMILLAN

LOOSE LEAF BINDER

Filed Dec. 12, 1925

Fig. 2.

Inventor:
John L. McMillan,
by *Dodge Pace*,
Attorneys.

UNITED STATES PATENT OFFICE.

JOHN L. McMILLAN, OF SYRACUSE, NEW YORK.

LOOSE-LEAF BINDER.

Application filed December 12, 1925. Serial No. 74,353.

This invention relates to loose leaf binders of the type in which the leaves are carried upon links or cross bars bridging the back of the book and engaged at opposite ends by pintles, the pintles of at least one end being carried by a longitudinally movable slide or bar so that they may be projected through or withdrawn from the links or cross bars to release the latter and 10 permit insertion or removal of sheets.

The invention consists in novel means for locking the movable slide or slides against longitudinal movement when in their engaging position, or unlocking them when 15 it is desired to effect such unlocking. In practice, it is desirable to permit locking and release of the sheet-carrying links or cross bars at either or both ends at will, so that sheets may be inserted or removed 20 at one or the other side of the body of leaves as may be more convenient.

The invention is illustrated in its preferred form in the accompanying drawings, wherein:

25 Figure 1 is an end view of a loose leaf binder embodying my invention, the cover-boards being broken away to permit the working parts to be shown of adequate size;

30 Fig. 2, a fragmentary face view looking into the binder, with the cover-boards thrown open or apart;

35 Fig. 3, a fragmentary sectional view of one of the pintle slide housings and of the box-like end of the back member of the binder, showing a portion of a pintle slide locked by a member of the locking mechanism, and also showing the lock shell or casing, the section being taken on the line 40 3-3 of Fig. 1;

Fig. 4, a perspective view of an end of one of the pintle slides and a fragment of the locking member which holds the same against end movement when in locking position, these parts being shown on a larger scale than in the other figures.

45 I have shown in the drawings two pintle slides, this being the preferred construction, but it is to be understood that one may be omitted and a simple wire or pintle rod used as a hinge-pin for one end of the leaf-carrying links.

The binder comprises a curved or approximately semi-circular back member 1, to opposite edges of which are hinged cover-

boards 2 and 3, here shown as secured to and carried by the pintle slide housings 4, though they will preferably be attached to the back member also by the covering 5 carried over the curved back member, and over outer faces and the edges of the boards and the housings when such covering is employed, or in a manner similar to the hinging of cover-boards of permanent book 60 bindings. This is conventionally illustrated 65 in Fig. 1, where the covering material 5 is shown carried over the back member and onto the cover-boards, or the housings which, under the construction here set forth, constitute portions of the cover-boards. The 70 ends of the back member 1 are provided with plates or heads, one of which, designated by the numeral 6, is shown in Figs. 1, 2 and 3, this head being of box-like form to receive within it parts of the locking 75 mechanism, whereas the opposite head or end plate may be a single sheet of metal or like material of similar outline.

The manner of forming the housing 4 is illustrated in Figs. 1 and 2, where it will 80 be seen that a sheet metal blank is bent or folded longitudinally near its midwidth, to produce at the folded edge a substantially cylindrical portion 4^a to receive the approximately cylindrical edge of one of the 85 pintle slides 7. Each slide is a flat bar of metal, one longitudinal edge of which is rolled, machined, or otherwise fashioned to produce a rounded or substantially cylindrical bead 7^a extending from end to end 90 of the slide. The bead or rounded edge of the slide is cut away at intervals to produce a plurality of pintles 8, of which there may be two, three, or more as deemed expedient for binders of different dimensions and de- 95 signed for different uses.

The pintles of each slide are in alignment with one another and register with eyes or transverse holes 9^a formed near each end of sheet-carrying links 9, which span the 100 back member 1 and pass through openings 10 formed in the housings 4 at such points as will permit the pintles to pass through and to withdraw from the eyes 9^a of the links 9 as the pintle slides are moved longitudinally in one or the other direction. The openings 10 are of a length to receive freely the link ends, but to prevent any material lateral play of the links therein, and they are cut deeply enough into the cylindrical 105 110

walls or portions 4^a of the housings 4 to permit the links to be swung upward when released by the pintles at either end, thus permitting the leaves to lie upon one cover-board when both boards are opened out flat and the links are disconnected at one end from one of the housings. With the leaves and links in such position, any desired number of leaves may be removed for the purpose of reaching a given leaf or leaves which it is desired to take out, or a point at which it is desired to insert a new leaf or leaves.

For the purpose of independently moving the pintle slides 7, each is furnished with a roughened thumb-plate 11 carried by a stem 12 shown by dotted lines in Fig. 2, said stem extending through an elongated slot or opening 13 in the housing, and riveted or otherwise made fast to the slide 7. The slot or opening 13 may with advantage be made of a length to limit and determine the extent of movement of the slide 7.

As indicated by dotted lines in Fig. 2, and shown in full lines in Figs. 3 and 4, the slide 7 is formed with a projecting stem 14 at the end nearest the box-like head 6, said stem being furnished with an enlarged head 14^a. When the pintle slides are adjusted to link-holding position as indicated in Figs. 2 and 3, the stems 14 protrude beyond the housings 4 and pass through openings into the box-like head 6, as best seen in Fig. 3.

Carried by the head 6 is a lock shell or casing 15, comprising a cylindrical body 15^a and a radial extension 15^b, as shown in Figs. 2 and 3. Within said body 15^a is the rotatable cylinder 16 of a lock of the Yale or Corbin type, the tumblers, pins and springs of which are sufficiently indicated in Fig. 3. The rotatable cylinder 16 is suitably secured in the head 6 and held against longitudinal movement, though free to turn within its shell 15. Projecting radially from the cylinder 16 and within the head 6, are two arms 17 and 18, shown by dotted lines in Fig. 1, and one of which (17) is shown by full lines in Fig. 3. Hinged or pivoted to the arm 17 is a link or bar 19, and similarly connected to the arm 18 is a bar 20, each bar formed or fashioned at the end remote from such pivotal connection, into a bifurcated or U-shaped head 21, best seen in Fig. 4. The seat in the head 21 is of a size to fit somewhat snugly about the stem 14, which it straddles when the lock cylinder is in the position in which it is shown in Figs. 1 and 3; that is to say, in the position in which it stands when the key 22 is inserted and removed.

To maintain the bifurcated ends of bars 19 and 20 in proper relation to the stems 14 of the pintle slides 7, suitable guides are provided near said bifurcated ends. These may be pins 26 passing through the walls of the hollow head 6; spurs or lips cut from

the inner wall of said hollow head and bent inward, as shown in Fig. 3; or any equivalent construction.

The parts being in the positions indicated in Figs. 1, 2 and 3, insertion of key 22 raises the pins 23 or moves them outward until their outer ends align at the circumference of said cylinder, their outward movement serving to force backward or outward the several tumblers 24 against the resistance of springs 25, as usual in locks of this type. When the key is withdrawn, the springs force inward the tumblers 24, which cross the meeting line of the rotatable cylinder 16 and the cylindrical shell 15, thus precluding rotation of the cylinder and hence holding the forked ends of the links 19 and 20 in engagement with the stems 14 of the slides 7. Said forked ends or heads of the links 19 and 20 are held by the walls of head 6 against lateral play and, passing under heads 14^a of stems 14, preclude longitudinal movement of the pintle slides 7; hence said slides are securely locked in place, and their pintles 8 cannot be withdrawn from the links 10.

From the foregoing description it will be evident that when it is desired to unlock the pintle slides 7, it is necessary only to insert the key and partially rotate cylinder 16 in a direction to withdraw the bifurcated heads 21 clear of the heads 14^a of stems 14, thus freeing the slides 7 and permitting either or both to be moved longitudinally by the thumb-plates 11, a distance sufficient to withdraw the pintles 8 from the links 9. Ordinarily only the slide will be moved which passes through the end of the links nearest the point at which an insertion or removal is to be made. When such removal or insertion is completed, the links will be swung back to normal position, and the slide or slides will be returned to link-engaging position, the key will be turned in the reverse or locking direction and withdrawn; and the book will then be safe against tampering with the leaves.

It will of course be understood that though I have shown the parts of the form and design which I deem most desirable, the invention contemplates such usual changes and adaptations as naturally fall within the field of the mechanic, and which conduce to convenience and economy of manufacture.

Any equivalent form of lock may be employed, that shown being selected because of its compactness and the difficulty of its being picked or opened by unauthorized parties.

For brevity and to shorten the claims, the phrase "loose leaf binder of the link and pintle type" will be used as indicating a binder such as shown and described, comprising a back member and two cover-boards hinged thereto, and a plurality of links

bridging the back member and hinged or pivotally connected at opposite ends to the cover-boards or to housings carried thereby, the hinged connection of at least one end being formed by a longitudinally movable pintle-bearing slide. Where a single pintle-bearing slide is employed and a permanent wire or hinge-rod is used for the opposite ends of the leaf-carrying links, one of the bars 19 or 20 will of course be omitted.

It will be noted that unlocking the pintle slides does not withdraw the pintles from the leaf-carrying links. Such withdrawal and re-engagement of the pintles is effected by means of the thumb-pieces 11, and either of said thumb-pieces may be operated at will and independently of the other. It is hence feasible and is the usual practice to move that slide which releases the end of the links nearest one or other face of the body of leaves constituting the bound mass. The pintles at the other end of the links in such case act merely as hinge pins.

While it is preferred to employ locking bars having a bifurcated end, it is obvious that any bar which through turning the key in locking direction shall be caused to enter a notch or recess in the pintle slide and prevent movement of the slide, may be employed.

It is obvious that the binding or clamping of the sheets or leaves is effected by the back member 1, the housings 4, the pintle slides 7, the links 9, the lock carried by a head of the back member, and the intermediate bars 19 and 20 which lock or release the pintle slides as the key is turned in one or the other direction. The cover-boards 2 and 3 merely serve to protect the bound leaves or sheets, and may if desired be omitted. When the cover-boards are used and connected with the housings in the manner illustrated and described, they become in effect integral and movable with the housings, or form extensions thereof, and are hinged or pin jointed to the back member by the pintles of slide 7 passing through the eyes of links 9. The housings 4, and consequently the cover-boards, are preferably further flexibly connected with or hinged to the back member by the covering material,—leather, canvas, buckram, or other,—usually applied as the outer covering or facing of the book cover or binding, or by this and other flexible sheet material introduced for the purpose. Owing, however, to the severe strains to which such connections are subjected in large and heavy books such as bank ledgers, minute books, and the like, a flexible connection of special and novel construction has been devised, and is made the subject-matter of an application for patent now pending before the Patent Office, filed in the name of another inventor but held in the same interest as the present application.

For this reason the flexible connection as contradistinguished from the pintle and link connection, is here shown only conventionally by the covering 5 in Fig. 1. It is not, however, essential that such additional hinge or flexible connection be used, and if the cover-boards be omitted, such connection may in some cases be advantageously omitted.

What is claimed is:—

1. In a loose leaf binder of the link and pintle type, a back member having a box-like end or head provided with openings near its extremities; a housing extending longitudinally of and located at one side of the back member; a slide movable in said housing and provided at its inner edge with a plurality of pintles and at one end with a headed stem projecting longitudinally from the slide in alignment with an opening of the box-like member, the housing being provided with link-receiving openings at its inner edge across which the pintles extend when the slide is moved in one direction and which are cleared by the pintles when the slide is moved in the opposite direction; leaf-carrying links extending across the back member and provided at opposite ends with eyes to receive the pintles and hinged at their opposite ends to the opposite edge of the back member; a fixed lock shell carried by the box-like head of the back member; a rotatable lock cylinder mounted within said shell and provided with a radial arm; tumblers carried by said lock and serving normally to prevent rotation of the lock cylinder; a bar pivotally connected at one end to the radial arm of the lock cylinder and bifurcated at its opposite end to receive or straddle the stem projecting from the end of the pintle slide; and a key serving to move the lock tumblers to cylinder-disengaging position and to rotate the lock cylinder for the purpose of effecting engagement and disengagement of the bifurcated bar with and from the headed stem of the pintle slide.

2. In a loose leaf binder of the link and pintle type a back member; housings at opposite longitudinal edges of said back member provided with link-receiving openings; pintle slides movable within said housings to carry their pintles across or clear of said openings, as the slides are moved in one or the other direction; leaf-carrying links bridging the back member and having eyes at their opposite ends to receive the pintles of the slides; a lock shell carried by a head of the back member; a key-actuated member within said shell; and locking bars connected with said key-actuated member and arranged to be moved into and out of locking engagement with the pintle slides by movements of the key-actuated member.

3. In a loose leaf binder of the character

described, a back member; slide housings at opposite sides of the back member provided with openings to receive leaf-carrying links; slides longitudinally movable in said housings and provided with pintles; leaf-carrying links bridging the back member, entering the housings through openings therein, and provided at their ends with eyes to

receive the pintles; a lock carried by the binder; and bars extending transversely to 10 and engageable with and disengageable from the pintle slides through manipulation of the lock.

In testimony whereof I have signed my name to this specification.

JOHN L. McMILLAN.
